FIG. 3.

UNITED STATES PATENT OFFICE.

CARL HOFFMAN, OF ALLENTOWN, PENNSYLVANIA.

AUTOMOBILE-SIGNAL.

1,383,632.

Specification of Letters Patent. Patented July 5, 1921.

Application filed August 16, 1920. Serial No. 403,753.

To all whom it may concern:

Be it known that I, CARL HOFFMAN, a citizen of the United States, and a resident of Allentown, in the county of Lehigh and State of Pennsylvania, have invented certain new and useful Improvements in Automobile-Signals; and I do hereby declare the following to be a full, clear, and exact description of the invention, such as will enable others skilled in the art to which it appertains to make and use the same.

My invention relates to signals for motor or other vehicles. It is particularly adapted for indicating to the traffic the direction the vehicle to which it is attached is to take or the fact that such vehicle is about to stop, and the object of my invention is to provide a simple and highly efficient device of this character so constructed that it will occupy but little space in the vehicle and the parts of which are arranged so that a single signal will give notice of a turn to the right or to the left or that a stop is to be made, at the will of the operator, and an additional object of the invention is the provision of means for automatically maintaining the signal in appropriate signal giving position until such time as it pleases the operator to release the signal.

In the drawings, Figure 1 is an elevation showing my improved signal, the parts being in non-signaling position. Fig. 2 shows the signal, in full lines, projected for indicating a left hand turn and in dotted lines for indicating a right turn. Fig. 3 shows the signal arranged for indicating a stop. Fig. 4 is a longitudinal sectional view showing the means for automatically maintaining the signal in projected position. Fig. 5 is a top plan view of the parts shown in Fig. 4.

1 indicates a supporting post to which, at its upper end, is pivoted a pair of arms 2, 3, which form the actuating means for the signal 4, the latter being of lazy tong form and having at its outer end an indicating member 5 which I have shown in the shape of a hand. The arms 3, 4 are crossed at their point of pivotal connection with the post 1 and a spring 6 maintains these arms in the position indicated in Fig. 1. An operating handle, shown as comprising two parts, 7 and 8, pivoted at 9, and respectively connected with the arms 2, 3 is arranged in convenient position for gripping by the driver. The pivotal connection between the

arms 3, 4 and the support 1 permits the signal to be turned as a whole about this point so that when projected, as indicated in Fig. 2 in full lines, the signal will extend downwardly so as to indicate that the vehicle is to turn to the left. The construction also permits the signal as a whole to be turned into the position shown in dotted lines in Fig. 2 to indicate a right turn.

In order that the signal may be maintained in projected position and to allow the driver of the motor vehicle to have free use of his hands I provide an automatic locking means which will hold the signal in such projected position until freed by the operator. Secured to the support 1 is a bracket 15 having lateral branches 16 extending in opposite directions. These branches have slots 17 receiving the lower ends of rods 18 one such rod being pivotally hung on a pin 19 projecting laterally from each of the arms 2, 3. Extending upwardly through appropriate openings in the bottoms of the branches 16 and into the slots 17 thereof, are pins 20. These pins are fixedly secured to a base plate 21, a coiled spring 22 between this plate and a collar 23 on the support 1 maintaining the plate in position to insure projection of its pins well up into the slots 17 and in the path of the rods 18. Movement of the arms 2 and 3 so as to project the signal straight out will tend to draw the lower ends of the rods 18 toward the support 1 thus bringing them into position to be blocked against outward movement by the pins 20. This effectively locks the signal in this projected position. It may be released by pressure on the plate 21, a lip 24 being conveniently arranged for that purpose or the operator may apply foot pressure to a rod 25 depending from the plate. Pressure so applied to the plate withdraws the pins 20 from the slots and the arms 2 and 3 will then be free to return to normal position under the influence of spring 6. In the event that is not desired to lock the signal in any projected position the plate 21 may be held down against the tension of its spring 22 and with the pins out of blocking position in the slots by a set screw 26 passing through a slot 27 in the rod 25 and into a standard 28 by which the support is carried. When the signal is to be projected upwardly the rod 18 secured to the arm 3 is alone effective for locking the signal in projected position, and when projected down-

wardly the rod 18 of arm 2 is the locking medium. The two inner pins 20 are for locking the signal in its farthest extended up or down position.

5. Suitable illuminating means such as an electric bulb appropriately connected with an energizing source may be carried by the signal member for night use.

Manifestly the post 1 may be supported 10 in any preferred manner in the vehicle. I prefer the form indicated in Fig. 1 which allows the post to be raised or lowered in the standard 28 to whatever height may be found desirable.

15. The advantages of my invention will be apparent. It is to be noted that I have produced a very simple signal which is effective for indicating all the necessary signals to the traffic in rear of the car, but a single signaling arm being effective to this end. The advantage of having a means for locking the signal in projected position is manifest. Frequently the driver of a car needs the use 20 of both hands in making a turn, and after he has given the indication of a contemplated 25 turn my device permits him to use both hands in operating the car without further thought of signaling to the man in the rear. After the turn is made the signal is readily 30 returned to its normal position simply by pressing on the rod 25 or on the plate to which the rod is attached.

I claim as my invention:

1. A signal including a support, an extensible signaling member pivotally secured to said support and adapted to be bodily turned on its pivot so as to project upward or downward when extended, and means for actuating said extensible member to extend 40 it, such means simultaneously turning said member on its pivot.

2. A signal including a support, an extensible signaling member pivotally secured to said support and adapted to be turned on its 45 pivot so as to project upward or downward

when extended, means for maintaining said member in extended upward or downward projected position, and means for rendering said last mentioned means ineffective.

3. A signal including a support, an extensible member pivotally secured to said support, said member being adapted to be extended in a horizontal plane and upward and downward at an angle to said plane from the pivotal connection with said support, means for maintaining said arm in any extended position, and means for rendering said last mentioned means ineffective.

4. A signal including a support, a pair of spring controlled arms pivotally secured to 60 said support, an extensible member of lazy tong form supported and adapted to be actuated by said arms and to be extended in a horizontal plane and upward and downward at an angle to said plane, a rod on each of 65 said arms, stops with which said rods are designed to engage to maintain said member in extended position, and means for supporting said stops, such means being operable to disengage said stops and rods to permit re- 70 turn of said member to normal position.

5. A signal including a support, a pair of spring controlled crossed arms pivotally secured to said support, an extensible member of lazy tong form supported and adapted to 75 be actuated by said arms and to be extended in a horizontal plane and upward and downward at an angle to said plane, levers for operating said arms, a rod on each of said arms, stops with which said rods are de- 80 signed to engage to maintain said member in extended position, tensioned means for supporting such stops, and a foot piece connected with such means for operating the same to disengage said stops and rods to permit return of said member to normal position.

In testimony whereof I have signed this specification.

CARL HOFFMAN.
